United States Patent Office.

DESIRE BIEVEZ, OF HAINE ST. PIERRE, BELGIUM.

Letters Patent No. 71,571, dated December 3, 1867.

IMPROVED OVEN FOR COOLING WINDOW-GLASS.

The Schedule referred to in these Letters Patent and making part of the same.

TO ALL WHOM IT MAY CONCERN:

Be it known that I, DÉSIRÉ BIEVEZ, of Haine St. Pierre, in the province of Hainaut, in the Kingdom of Belgium, have invented a new and improved Oven for Cooling Window-Glass; and I do hereby declare that the following is a full and exact description thereof, reference being had to the accompanying sheet of drawings, and to the letters of reference marked thereon.

Figure 1 is a transverse vertical section of one of the frames, hereinafter referred to. A is the bed of the oven; B B are the upright portions of the frame, working in the slides or grooves in the wall of the oven; C is one of the transverse bars, c c c c c being the chairs with the grooved rollers, hereinafter mentioned.

Figure 2 is the hereinafter-mentioned horizontal connecting-bar, to which the lever is attached.

Figure 3 is a longitudinal section of a frame. A is the bed of the oven, a being the crown or arch of the same. B is the lever by which the upward and downward motion of the frame is effected. C, horizontal connecting-bar. D, counterbalance-weights. E, longitudinal-bar in bed of the oven.

Figure 4 is a horizontal view of the bed of the oven, with the transverse and longitudinal bars.

Now the oven, which is the subject of my said invention, is constructed of a rectangular form, and of the usual materials, and is placed by the side of the ordinary spreading-furnace, with which it communicates, and from which the glass to be cooled is introduced on a movable table into the oven. At the side of the oven, and behind the spreading-furnace, is a small furnace, the heat from which circulates under the bed of the oven, and keeps it at the required temperature. At equal distances in the side walls of the oven are provided a number of cast-iron upright slides or grooves, in which are placed; so as to work freely therein, a corresponding number of iron frames, the bottom transverse portions of which rise and fall in grooves made in the bed of the oven for their reception, whilst their top portions project beyond the crown or arch of the oven, where they are all connected by a horizontal bar. Each frame is furnished with a counterbalance-weight, to facilitate its upward and downward motion, which motion is given by a lever placed at the end of the connecting-bar. On the upper surface of the transverse bottom pieces of the said iron frames, chairs are placed, at equal distances, each containing a grooved roller, and on each of which rollers a flat iron bar is placed longitudinally. These bars are connected by a cross-piece at that end of the oven at which the glass is withdrawn, when sufficiently cooled, and extend towards the mouth of the oven, to the point where the movable table carrying the glass to be cooled enters it at right angles from the spreading-furnace. The said bars, when not in use, are received into longitudinal grooves prepared in the bed of the oven, leaving the surface of the bed perfectly flat and even.

To enable others skilled in the art to construct and work my invention, I will now describe the action of the apparatus, which is as follows:

A sheet of spread glass having been conveyed on the movable table from the spreading-furnace to the cooling-oven, it is placed by the workman on the end of the bed thereof, where it remains until the spreader has another sheet ready, when, by the action of the said lever, placed at the end of the horizontal bar connecting the frames, the latter are raised up from the grooves in the bed of the oven, bringing up with them the longitudinal bars lying on the grooved rollers fixed to the bottom cross-pieces of the frames, and consequently the sheet of spread glass lying on the bed of the oven, the said bars affording the glass a perfect support. By means of the cross-piece connecting the longitudinal bars at one end, they can be moved horizontally all together, and they are then drawn out to something more than the width of the sheet of glass, bringing it with them the same distance towards the door, from which it will issue when sufficiently cooled. The action of the lever is then reversed, the cross-pieces of the frames and the longitudinal bars fall again into their respective grooves, and the displaced sheet of glass lies again perfectly flat on the bed of the oven. The longitudinal bars are then pushed in again over the grooved rollers, and the oven is ready to receive the second spread sheet, the place occupied by the first being vacant now. A third sheet being ready, the same operation is repeated, and so on until the first sheet put in arrives at the end of the oven gradually and equally cooled in every part, and perfectly straight, the workman having only to place it upright on the ground.

What I claim as my invention, and desire to secure by Letters Patent, is—

The lifting-frames, constructed, arranged, and operating substantially as and for the purpose herein specified.

I also claim the movable longitudinal bars, for moving the glass sheets or plates along, substantially as herein set forth, in combination with the lifting-frames.

I also claim the grooved oven-bed, for the reception of the transverse bars of the lifting-frame, and the longitudinal moving-bars, substantially as herein specified.

Brussels, sixteenth January, one thousand eight hundred and sixty-seven.

DÉSIRÉ BIEVEZ.
